UNITED STATES PATENT OFFICE.

STEPHEN B. MORSS, OF RAHWAY, NEW JERSEY.

LAMP-BURNER.

SPECIFICATION forming part of Letters Patent No. 701,919, dated June 10, 1902.

Application filed August 21, 1901. Serial No. 72,760. (No model.)

To all whom it may concern:

Be it known that I, STEPHEN B. MORSS, a citizen of the United States, residing at Rahway, State of New Jersey, have invented certain 5 new and useful Improvements in Lamp-Burners, of which the following is a specification.

My invention has reference more particularly to the class of lamp or oil-stove burners which have a central draft or air flue to conduct air to the flame; and the object of the invention is to provide improved means for protecting the top of the wick to produce a substantially even flame, to distribute air in proper proportion to the flame and directly 15 at the base of the flame whereby to increase the steadiness of the latter, and to also extinguish the flame when the wick is turned low and at the same time to prevent gases from rising from the wick-top.

20 A further object of the invention is to provide improved means for regulating or limiting the height to which the wick can be turned up, so as to prevent the wick from being turned up so high as to produce smoke.

25 In carrying out my invention I provide a perforated cone or thimble having an inwardly-projecting flange or rim beneath the perforations that is adapted to rest upon the lamp-wick, whereby the latter can raise and 30 lower the cone or thimble, and means are provided for guiding the cone or thimble as it is moved by the wick.

The invention also consists in the combination of wick-casing tubes and a cone or 35 thimble having a guiding portion with a stop interposed between one of the tubes and said guiding portion to regulate and limit the vertical movement of the cone or thimble when it is raised by the wick.

40 The invention also consists in the novel details of improvement that will be more fully hereinafter set forth and then pointed in the claims.

Reference is to be had to the accompanying 45 drawings, forming part hereof, wherein—

Figure 1 is a side elevation of a portion of a lamp-burner embodying my improvement. Fig. 2 is a plan view of the burner with the air cone or thimble removed. Fig. 3 is a 50 perspective view of the air thimble or cone, and Fig. 4 is a detail side view showing a modification.

In the accompanying drawings, in which similar numerals of reference indicate corresponding parts in the several views, 1 indicates a perforated thimble, cone, or air-distributor, which may generally be of ordinary or suitable construction in so far as the air-distributing portions are concerned, and beneath its perforations the cone or thimble is provided with an inwardly-extending flange or rim 1^a, that is adapted to rest upon a wick 2, that is contained in the usual manner between the wick-casing tubes 3 4, any suitable means (not shown) being provided for 55 raising and lowering the wick. By this means the cone or thimble is enabled to be made of such width as to extend over the wick, and thereby when the latter is raised from the tubes and the oil lighted the flame will burn 60 from the side of the wick above the outer tube 3, the air from the perforations in the cone or thimble will be directed close to the base of the flame, and the heated cone or thimble, and particularly the flange resting upon the wick, 65 will act in the nature of a gasifier of the oil from the side of the wick above the outer tube 3, the air from the perforations in the cone or thimble will be directed close to the base of the flame, and the heated cone or thimble, and particularly the flange resting upon the wick, 70 will act in the nature of a gasifier of the oil when the wick is raised and in use, thereby increasing the brilliancy of the flame. Furthermore, the flange 1^a protects the top of the wick from being burned, and a more even flame results than where the flame is burned at the top of the wick in well-known manner. It will also be seen that as the cone or thimble has 75 such a width as to extend over the wick a larger supply of heated air is maintained in 80 proximity to the wick for a given height of cone or thimble than is possible with the cones or thimbles of well-known construction heretofore in use that did not extend over the wick. The cone or thimble 1 is also provided with 85 a depending guiding portion 1^b, that is shown passing into the tube 4, whereby as the thimble is raised and lowered by the wick it will be guided in a vertical direction and maintained in proper position upon the wick and 90 also kept from tilting, so as to prevent flame from burning at the top of the wick. To prevent the flame from being raised too high, I provide one or more stops interposed between the wick-casing tube and the thimble, and 95 for this purpose I have shown the tube 4, provided with pins or projections 5, that extend inwardly and pass through slots 1^c in the guide 1^b of cone 1. The slots I have shown

are in the nature of bayonet-joint or L-shaped slots. The portion 1^d of the slots 1^c is of considerable height or of such height as to regulate definitely the height to which the wick 5 can be turned, because the pins 5 are adapted to project into the slot 1^c, as shown in Fig. 1. When the cone or thimble is placed in position upon tube 4, the vertical part of the slot 1^c first receives the pin 5 and then the cone 10 is turned to carry the pin into the portion 1^d of the slot, and thereby as the wick is raised the bottom edge of the slot will encounter the wick to prevent the latter from being raised too high. The lip 1^e of slot 1^c prevents the cone 15 or thimble from becoming loosened or dropping off the lamp when the latter is handled. This stop for the cone or thimble is simple and effective and one that can readily be understood by those accustomed to using lamps.

20 Any desired number of such slots and pins can be used, and I have shown four of them which will tend to maintain the thimble in a substantially horizontal position when raised by the wick or, in other words, will tend to 25 prevent the cone from becoming tilted.

The wick can be turned to any intermediate height within the vertical limits of portion 1^d of slot 1^c, and the relative arrangement of the slot or pin is such that when the wick is turned 30 down sufficiently far the cone or thimble will rest upon tubes 3 3, will thus act to extinguish the flame, and will prevent gases from escaping.

If desired, the flange 1^a can be imperforate 35 or perforated or slotted or fluted or grooved horizontally. This latter arrangement is shown in Fig. 4, wherein the flange or rim 1^a is grooved, fluted, or corrugated radially, as at 1^e. When such flange or rim rests upon 40 the wick, radial spaces are formed between the flange and the wick in which gas or vapor may collect, and the latter will be distributed to the flame, with the effect of increasing com-

bustion and brilliancy of the flame. When the flange or rim 1 is perforated, gases that 45 rise from the surface of the wick will enter the perforated cone or thimble and will be distributed mixed with air to the flame with the advantage of increasing the brilliancy of the latter.

50 I do not limit my invention to the precise details shown and described, as they may be varied without departing from the spirit thereof.

Having now described my invention, what 55 I claim is—

1. In a central-draft burner a wick and an air-distributer having an inwardly-extending flange or rim resting upon and supported by the wick whereby the distributer will be 60 raised and lowered by the wick, substantially as described.

2. In a central-draft burner, the combination of wick-casing tubes and a wick therebetween with a perforated air-distributer having an inwardly-extending flange or rim resting upon the wick when the latter is raised above the tubes and acting as an extinguisher by closing the space between the tubes when the wick is turned down, the distributer being provided with a depending guide guided to travel along the tube to direct the vertical movement of the distributer when raised or lowered by the wick, substantially as described.

75 3. As an article of manufacture, a perforated air-distributer for a lamp or stove having a flange or rim to overlie a wick, said flange or rim having grooves providing spaces between the wick and the flange or rim to receive gas or vapor, substantially as described.

STEPHEN B. MORSS.
